SPREADER STOKER APPARATUS

Donald J. Mosshart, Ardmore, Pa., assignor to
Westinghouse Electric Corporation, East Pitts-
burgh, Pa., a corporation of Pennsylvania

Application October 8, 1945, Serial No. 621,060

11 Claims. (Cl. 110—101)

1

This invention relates to furnace controls, more particularly to controls for maintaining a fuel bed of predetermined thickness characteristics, and has for an object to provide improved control apparatus of this character.

Another object of the invention is to provide control apparatus for a furnace whose fuel bed comprises first and second zones, the control apparatus functioning to maintain a predetermined ratio of fuel bed thickness of the two zones.

A further object of the invention is to provide, in a "spreader" type stoker, means for controlling the location of the spreading of fuel on the fuel bed in response to changes in the ratio of rates of flow of primary air to various sections of the fuel bed.

Yet another object of the invention is to provide, in a "spreader" type stoker, control mechanism for varying the trajectories of fuel being "spread" on the fuel bed in response to changes in the ratio of rates of flow of primary air to different portions of the fuel bed.

These and other objects are effected by the invention as will be apparent from the following description and claims taken in connection with the accompanying drawings, forming a part of this application, in which:

Fig. 1 is a diagrammatic view, partially in section, of stoker apparatus embodying the principles of the present invention; and

Fig. 2 is an enlarged fragmentary view of a modification of a portion of the structure shown in Fig. 1.

Referring now to the drawing more in detail, reference character 10 indicates, in its entirety, a stoker installation of the "spreader" and the "sprinkler" type, together with a chain grate type of fuel-supporting surface disposed in the bottom of a furnace between the front wall 11 and the rear wall 12 of the latter.

The fuel-feeding mechanism comprises a hopper 13 and one or more rams 14 adapted to feed fuel from the hopper rearwardly through a fuel compartment 15 and over the rear discharge edge of a spill plate 16, the position of the latter being adjustable in a front to rear direction by suitable means, such as an operating rod 17. The fuel, pushed rearwardly by the ram 14 and falling by gravity from the rear discharge edge of the spill plate 16, is struck by the blades 18 of the rotary impeller 19 and is projected rearwardly through the opening 21 in the furnace front wall to fall through the atmosphere about the chain grate 22, the fine fuel being burned in suspension and

2

the larger particles thereof falling to the grate surface where they are consumed during the time they are being carried by the moving grate surface to the ash pit 25, below the rear discharge end of the chain grate. The chain grate operates in the usual manner, being carried by sprockets 23 and 24 and serving to progressively advance the fuel from the vicinity of the front wall 11 to the ash pit 25 beneath the furnace rear wall 12.

Wall structure, such as shown at 26, 27 and 28 serves to define a main plenum chamber 29, positioned beneath the effective area of the chain grate 22. Partition members 31 and 32 are disposed within the main plenum chamber 29 in such a manner as to divide a portion of the interior of the latter into two secondary plenum chambers A and B. This partition structure 31, 32 is provided with inlet orifices 33 and 34 for the secondary plenum chambers A and B, respectively, for admission of air to the latter from the main plenum chamber 29, this air being provided from any suitable source such as the centrifugal blower 35.

Supplementary partition members 36, 37 and 38 are positioned within the grate structure between the upper and lower courses thereof, and constitute, in effect, continuations of the wall and partition members 26, 32 and 27, respectively, with the result that the secondary plenum chambers A and B extend upwardly to the under surface of the upper course of the chain grate 22. While in the construction herein illustrated the orifices 33 and 34, providing for admission of primary air to the secondary plenum chambers 35 A and B, are of fixed sizes, it will be obvious that they may be made adjustable in effective cross-sectional area, if desired, in order to obtain any desired ratio of rate of flow of air to the two zones of the fuel bed overlying the plenum chambers A and B.

It will be apparent that, with the orifices 33 and 34 of fixed effective cross-sectional area, or of any predetermined cross-sectional area, the rate of flow of air to the plenum chambers A and B will be dependent upon the thickness of the fuel bed areas overlying the two plenum chambers. If for any reason the thickness of the fuel bed section overlying the plenum chamber B, for example, should become materially thinner than the fuel bed section overlying the chamber A, a relatively greater quantity of air would pass through the chamber B, thereby resulting in excess combustion of fuel in the fuel bed section overlying the chamber B, thus further thinning the fuel bed and increasing the un-

balanced condition existing between the two sections of fuel bed.

It is the purpose of the present invention to provide novel means for counteracting or eliminating such unbalanced conditions and to this end there is provided control apparatus, indicated in its entirety by the reference character 40.

A pair of diaphragms 41 and 42 are housed within casings 43 and 44, respectively, the spaces at the upper sides of the diaphragms 41 and 42 being in communication, through conduits 46 and 47, respectively, with the interiors of the plenum chambers A and B, with the result that changes in the pressures existing within these plenum chambers will be transmitted to the diaphragms to cause movement of the latter.

Any such movement of the diaphragms 41 and 42 is transmitted through rods 48 and 49, respectively, to a link 50, fulcrumed at 51 to a fixed support 52. The rods 48 and 49 are pivotally connected to the link 50 at opposite sides of the fulcrum 51, as at 53 and 54, respectively.

One end of the link 50 is pivotally connected, at 55, to the free end of arm 56 of a bell crank 57, pivotally mounted as at 58, on a fixed support 59. The other arm 61 of the bell crank carries a single-pole, double-throw mercury switch 62.

The mercury switch 62 controls a circuit, indicated in its entirety by a reference character 63, which conveys electric power from a source S' to a reversible motor 64, this motor constituting the driving means for a gear box 65 which operates a rheostat 66 disposed in the circuit 67 which supplies power from the source S to a variable speed motor 68, this motor continuously rotating the rotary impeller 19 of the spreader stoker. Preferably, the gear box 65 has an input to output ratio which will require the consumption of several minutes (5 to 15) for adjustment of the rheostat through its entire range to vary the speed of the impeller driving motor 68 from minimum to maximum R. P. M.

In operation, if the fuel bed section overlying the plenum chamber B becomes thinner than that overlying the plenum chamber A, for any reason, such as change in the size or moisture content of the fuel, the ratio of air pressures within the chambers A and B will be consequently varied, the pressure in the chamber B decreasing and resulting in upward movement of the diaphragm 42 and consequent tilting of the link 50 with the end 55 thereof moving downward so that the mercury in the switch 62 will flow to the right-hand end thereof as viewed in Fig. 1. This will energize that part of the circuit 63 which causes the motor 64 to rotate in a direction tending to decrease the resistance of the rheostat 66 with consequent increase in the speed of the variable speed motor 68. Due to the low gear ratio of the gear box 65, several minutes will be consumed in the gradual speeding up of the motor 68 and of the rotary impeller 19. As the revolutions of the rotary impeller 19 increase, the blades 18 thereof will contact, with heavier impacts, the fuel fed from the rear discharge edge of the spill plate, resulting in increased trajectories of the fuel entering the furnace and disposition of the fuel at points nearer the rear of the chain grate. As the speed of the rotary impeller increases, the fuel will be deposited farther and farther rearwardly on the chain grate until the greater portion of the fuel is being deposited on the portion of the fuel bed overlying the plenum chamber B, with the result that the thickness of that section

will increase to a point where the resistance to flow of air therethrough from the chamber B is greater than the resistance to flow of air from the chamber A. When this condition is reached, the air pressure in the chamber A will be lower than that in the chamber B and the action of the diaphragms 41 and 42 and of the linkage controlled thereby will cause reversal of the position of the mercury switch 62 with consequent reversal of gear box input motor 64 and reversal of the direction of the movement of the rheostat 66. This will result in a gradual slowing down of the rotary impeller driving motor 68 and the consequent shortening of the trajectories of the fuel impelled by the rotary impeller until such time as the air balance between the two plenum chambers again reverses.

If it is desired to maintain a thicker fuel bed on the portion of the grate overlying one plenum chamber than on the portion overlying the other chamber, this may be obtained by adjustment of the location of the fulcrum 51 by proper selection of the pivot hole 60 in the link 50 for reception of the fulcrum 51.

In Fig. 2, there is illustrated a modification of the fuel trajectory-varying mechanism, wherein the rotary impeller 19 rotates at a predetermined speed and variation of the trajectories is obtained by adjustment of the front to rear position of the spill plate 16. Obviously, if the spill plate 16 is moved forwardly or to the left as viewed in Fig. 2, the blades 18 of the rotary impeller will tend to strike the fuel before the blades have reached a vertical position, with the result that the trajectories of the fuel are higher and the fuel thrown well to the rear of the grate surface. On the other hand, if the spill plate 16 is moved rearwardly or to the right as viewed in Fig. 2, the blades 18 will have passed a vertical position before striking the fuel falling from the rear discharge edge of the spill plate, with the result that the trajectories of the fuel will be substantially below the horizontal with the fuel falling on the forward portion of the grate.

With this control, a circuit 63', corresponding to the circuit 63 of the previously-described arrangement, is controlled by diaphragms, linkage and mercury switch arrangement similar to that shown in Fig. 1. The circuit 63' likewise serves to reverse the motor 68 driving a gear box 71 which in turn works through a worm gear drive 72-73 carried by the shaft 74 of the spill plate 16 to move the latter forwardly or rearwardly, depending on the direction of rotation of the motor 68. As in the arrangement of Fig. 1, the gear box input to output speed ratios are such that several minutes will elapse for complete travel of the spill plate in any one direction.

In order to limit forward or rearward positions of the spill plate 16, the rod 74 carries a pair of spaced contacts 75 and 76, disposed at opposite sides of a contact 77. When the spill plate 16 reaches its forward limit of movement the element 75 will contact the element 77 and close the circuit 78 to energize the solenoid 79, thus opening the switch 81 in the part of the circuit 63' which is energizing the reversible motor 68, to cause forward movement of the spill plate 16. With this part of the circuit 63' open, the motor 68 will be idle and the spill plate 16 will remain in its forwardmost position until change in the air pressure ratio of the two plenum chambers results in change in position of the mercury switch and consequent energization of the other half of the circuit 63', causing

energization of the motor for rotation in the opposite direction, whereupon the spill plate 16 will be moved forwardly or to the left. As soon as the spill plate moves to the left, the contact between the elements 15 and 77 is broken, the solenoid 78 deenergized and the switch 81 closed, with the result that the part of the circuit 63' which includes the switch 81 will be ready for use upon further change in the air balance of the control system.

Movement of the spill plate to the left or forward is likewise limited by engagement of contacts 78 and 77 to energize the solenoid 82 and open the switch 83.

While the invention has been illustrated as applied to a chain grate type of stoker, it will be apparent that it may be used to equal advantage with any type of fuel-supporting surface.

While the invention has been shown in several forms, it will be obvious to those skilled in the art that it is not so limited, but is susceptible of various other changes and modifications without departing from the spirit thereof.

What is claimed is:

1. Apparatus of the character described, comprising means providing a fuel-supporting surface, means providing a pair of plenum chambers beneath said fuel-supporting surface, fuel-feeding mechanism of the "spreader" or "sprinkler" type for feeding fuel to said fuel-supporting surface through the atmosphere thereabove, and means for automatically varying the ratio of the quantity of fuel fed to the surface overlying one of the plenum chambers to the quantity of fuel fed to the surface overlying the other plenum chamber in response to changes in the ratio of thickness of the fuel bed overlying the two plenum chambers.

2. Apparatus of the character described comprising means providing a fuel-supporting surface, means providing a pair of plenum chambers beneath said fuel-supporting surface, means for supplying air to said plenum chambers, means for spreading fuel on said fuel-supporting surface through the atmosphere thereabove, and means for automatically shifting the deposition of the majority of fuel fed by said fuel-spreading means from one portion of said fuel-supporting surface to another portion thereof in response to changes in the ratio of the rate of flow of air to one plenum chamber to the rate of flow of air to the other plenum chamber.

3. Apparatus of the character described comprising means providing a fuel-supporting surface; means cooperating with said first-mentioned means to provide below the latter a pair of plenum chambers; fuel-feeding means of the "spreader" type, disposed externally of the vertical projection of said fuel-supporting surface, for spreading fuel onto a portion of said fuel-supporting surface through the atmosphere thereabove; and means, responsive to changes in the ratio of air pressures in the two plenum chambers, to shift the deposition of fuel fed by said fuel-feeding means from one portion of said fuel-supporting surface to another portion thereof.

4. Apparatus of the character described comprising means providing a fuel-supporting surface; means cooperating with said first-mentioned means to provide below the latter a pair of plenum chambers; fuel-feeding means of the "spreader" type for projecting fuel onto a portion of said fuel-supporting surface through the atmosphere thereabove, said fuel-feeding means

including a rotary impeller and means for rotating the latter at varying speeds, whereby the trajectories of the fuel projected thereby onto the fuel-supporting surface are varied, with corresponding variations in the area of the fuel-supporting surface on which the fuel is spread; and means responsive to changes in the ratio of air pressures in the two plenum chambers resulting from changes in the relative resistance of the two portions of fuel bed, overlying the two plenum chambers, to flow of air therethrough from said plenum chambers, to automatically vary the speed of rotation of the rotary impeller.

5. Apparatus of the character described comprising means providing a fuel-supporting surface; means cooperating with said first-mentioned means to provide below the latter a pair of plenum chambers; fuel-feeding means for projecting fuel onto a portion of said fuel-supporting surface through the atmosphere thereabove, said fuel-feeding means including a rotary impeller and a variable speed engine for rotating the impeller at various speeds, whereby the trajectories of the fuel propelled thereby onto the fuel-supporting surface may be varied with corresponding variation in the area of the fuel-supporting surface on which the fuel is spread; means for supplying constant ratios of volumes of air to the two plenum chambers for discharge through the bed of fuel thereabove; and means, responsive to changes in the relative resistances of the portions of the fuel bed overlying the two plenum chambers to flow of air therethrough, to vary the speed of the engine driving the rotary impeller.

6. Apparatus of the character described comprising means providing a fuel-supporting surface having first and second zones; means cooperating with the first-mentioned means to provide below the latter first and second plenum chambers associated with the first and second zones of the fuel-supporting surface, respectively; fuel-feeding mechanism disposed beyond one end of the first zone of the fuel-supporting surface, with the second zone extending from the opposite end of the first zone, said fuel-impelling mechanism being adapted to impel fuel onto the two zones through the atmosphere thereabove, said fuel-feeding mechanism including means for varying the impelling force exerted by said mechanism on the fuel from a minimum to a maximum, whereby when minimum force is exerted, the fuel is deposited on the first zone of the fuel-supporting surface and when maximum force is exerted, the fuel is deposited on the second zone; means for supplying air to the two plenum chambers at constant pressures, for discharge through the fuel thereabove; and means responsive to changes in the ratios of the pressures within the two plenum chambers, which changes result from variations in the resistance of the fuel thereabove to flow of air therethrough, for varying the impelling force exerted on the fuel being fed by the fuel-feeding mechanism, to vary the relative quantities of fuel deposited on the two zones in inverse relation to the changed pressure relations in the two plenum chambers therebelow.

7. Apparatus of the character described comprising means providing a fuel-supporting surface having first and second zones disposed in end-to-end relation; fuel-feeding mechanism disposed in longitudinal alignment with the two fuel-supporting surface zones and including an impeller rotatable about a horizontal axis and adapted to

spread fuel on the first zone through the atmosphere thereabove and on the second zone through the atmosphere above both zones, and means for rotating said impeller at speeds variable between a minimum speed at which the majority of the fuel is spread on the first zone and a maximum speed at which the majority of the fuel is spread on the second zone; and means responsive to changes in the relative thicknesses of the fuel beds on the two zones for varying the speed of rotation of the rotary impeller and consequently the area of the fuel-supporting surface on which the fuel is deposited to return the fuel bed thicknesses to their original ratio.

8. Apparatus of the character described comprising means providing a fuel-supporting surface having first and second zones disposed in end-to-end relation; means cooperating with the first-mentioned means to provide below the latter first and second plenum chambers communicating with the first and second zones, respectively, of the fuel-supporting surface; fuel-feeding mechanism disposed in longitudinal alignment with the two zones of the fuel-supporting surface and including an impeller rotatable about a horizontal axis and adapted to spread fuel on the first zone through the atmosphere thereabove and on the second zone through the atmosphere above both zones, and means for rotating said impeller at speeds variable between a minimum at which the majority of fuel is spread on the second zone; means for supplying constant ratios of volumes of air to the two plenum chambers for discharge therefrom through the beds of fuel on the two zones thereabove; and means, responsive to changes in the ratio of air volumes supplied to the two plenum chambers resulting from changes in the ratio of thicknesses of the fuel beds overlying the two plenum chambers, for controlling the driving means for the rotary impeller to vary the rotative speed of the latter, whereby the deposition of fuel is shifted from one zone of the fuel-supporting surface to the other zone thereof to return the fuel bed thicknesses to their original ratio.

9. Apparatus of the character described comprising means providing a fuel-supporting surface having first and second zones disposed in end-to-end relation; fuel-feeding mechanism aligned with the two zones of the fuel-supporting surface and including means for projecting fuel to the first zone through the atmosphere thereabove and to the second zone through the atmosphere above both zones, and means for varying the trajectories of the fuel as they are projected to the zones of the fuel-supporting surface, whereby with decreasing trajectories, the majority of the fuel is deposited on the first zone and with increasing trajectories an increasingly larger portion of the fuel is deposited on the second zone; and means, responsive to changes from desired relative thicknesses of the fuel beds on the two zones, for adjusting the trajectory-varying means to vary the location on the fuel beds of the deposition of the majority of the fuel to reestablish the desired relative thicknesses of fuel beds on the two zones.

10. Apparatus of the character described comprising means providing a fuel-supporting surface; means cooperating with the first-mentioned means to provide beneath the latter a pair of plenum chambers, one of which is adapted to discharge air through the fuel bed on a first zone of the fuel-supporting surface thereabove and

the other of which is adapted to discharge air through the fuel bed on a second zone of the fuel-supporting surface thereabove; fuel-feeding mechanism including means for projecting fuel to the first zone through the atmosphere thereabove and to the second zone through the atmosphere above both zones, and means for varying, between limits, the trajectories of the fuel particles as they are projected to the zones of the fuel-supporting surface, the limits being such that at the minimum the majority of the fuel falls on the first zone and at the maximum the majority of the fuel falls on the second zone; and means for controlling the trajectory-varying means, said last-mentioned means comprising a speed reducer having an input shaft and an output shaft, a reversible motor adapted to drive said input shaft, means for reversing said motor in response to increases and decreases in the ratio of pressures in the two plenum chambers with respect to a selected ratio, and means operatively connecting the output shaft of the speed reducer with the trajectory-varying means, whereby with the reversible motor operating in one direction the fuel trajectories are gradually increased and with the motor operating in the other direction, the fuel trajectories are gradually decreased.

11. Apparatus of the character described comprising means providing a fuel-supporting surface having first and second zones disposed in end-to-end relation; fuel-feeding mechanism aligned with said two zones of the fuel-supporting surface and including an impeller rotatable about a horizontal axis, a spill plate disposed with its rear discharge edge overlying the rotary impeller and said spill plate being adjustable in front to rear directions with respect to a vertical plane containing the axis of rotation of the impeller, and means for feeding fuel along said spill plate for gravitational discharge from the rear discharge edge thereof to the rotary impeller therebelow, adjustment of the spill plate to a position with its discharge edge disposed forwardly of the vertical plane of the axis of rotation of the impeller producing high trajectories of fuel from the impeller with the majority of the fuel passing through the atmosphere above said first and second zones of the fuel-supporting surface and being deposited on said second zone, and adjustment of the spill plate to a position with its discharge edge disposed rearwardly of the vertical plane of the axis of rotation of the impeller producing relatively low trajectories of fuel from the impeller with the majority of the fuel passing through the atmosphere above said first zone of the fuel-supporting surface and being deposited thereon; and means, responsive to changes from the desired relative thicknesses of the fuel beds on the two zones, for adjusting the spill plate forwardly and rearwardly to vary the location on the fuel beds of the deposition of the majority of fuel beds, to reestablish the desired relative thicknesses of the fuel beds on said two zones.
